UNITED STATES PATENT OFFICE.

JOHN STRAKA, OF CHICAGO, ILLINOIS.

BALL-SHOOTER.

1,244,793.

Specification of Letters Patent. Patented Oct. 30, 1917.

Application filed December 22, 1916. Serial No. 138,375.

To all whom it may concern:

Be it known that I, JOHN STRAKA, a subject of the Emperor of Austria-Hungary, residing at Chicago, in the county of Cook and State of Illinois, have invented certain new and useful Improvements in Ball-Shooters, of which the following is a specification.

This invention relates to improvements in ball shooters. The principal object is to provide a device that may be used as a billiard or pool cue or as a toy marble shooter. A further object is to provide a shooter of this type in which the force or impact of the shot is manually controlled by a skilled or practised operator. A further object is the provision of mechanical means within the shooter for regulating, in a measure, the force or impact of the shot. A further object is to provide a shooter with hammer mechanism whereby a blow may be struck to drive the ball without moving the shooter after it has been properly positioned for directing a shot. A further object is to provide a device of this class that is simple in construction, efficient in operation and cheap to manufacture.

With the foregoing and other objects in view the invention consists in the combination and arrangement of parts to be hereinafter fully described in this specification, pointed out in the claims and illustrated in the accompanying drawing which forms a part of the specification and in which

Figure 1 is a sectional view of the device in side elevation.

Fig. 2 is a top plan view of Fig. 1.

Fig. 3 is a fragmentary sectional view with the movable parts in an altered position.

Fig. 4 is a fragmentary view of a slightly modified form of the device.

Like reference characters denote corresponding parts throughout.

The reference numeral 1 denotes the barrel of the shooter which is formed with a hollow extension 2 that serves as a bearing for the trigger and connections. Referring now to the first three figures of the drawing, the reference numeral 3 denotes the trigger which terminates in the finger piece 4 and that is fulcrumed upon the pivot pin 5 car-

ried by the said extension 2. A pawl 6 fulcrumed upon a pin 7 carried by the trigger has one end in engagement with a leaf spring 8 terminally secured by rivet 9 to said trigger, the working end of said pawl being normally in engagement with one of the teeth of the ratchet 10 which is pivotally disposed upon the said pin 5. The ratchet 10 is formed with the heel 11 adapted for engagement with a shoulder 12 formed on the extension 2 for the purpose of limiting the movement of the said ratchet in one direction. The ratchet 10, further, is formed with an integral arm 13 which is connected by the link 14 with the plunger rod 15 which extends a considerable distance beyond one end of the barrel 1 and is provided throughout the greater part of its length with the tapered tubular casing 16 which is fast thereto and is formed at its larger or inner end with the head 17 covered by the metal cap 18 against which one end of the spiral expansion spring 19 abuts which spring encircles the plunger rod and also abuts an annular stop ring 20 disposed in the bulged portion of the said barrel.

In Fig. 1 the shooter is shown in normal position. To operate the same the plunger 1 is manually depressed toward the barrel 1 which movement will cause spring 8 and pawl 6 to move the ratchet about the pin 5 and move the arm 13 toward the closed end 22 of the casing thus pulling the plunger rod 14 and tube 16 into the barrel and compressing the spring 19. At a certain point in the movement of the trigger the pawl will contact with a lug 23 of extension 2 and such contact will be made known to the operator by the resistance against the further downward movement of said trigger. Further pressure upon the trigger will, however, flatten the spring 8 against the trigger and at the same time disengage the pawl from the teeth of the ratchet thus releasing said ratchet and permitting the sudden expansion of spring 19 with a resultant outward thrust of the plunger rod for contact or shooting engagement with the ball or marble into immediate proximity with which the free end of the plunger rod has been placed previous to movement of the trigger. The movement of the spring into expanded

position will automatically reset the pawl and ratchet and trigger for the next shot. I prefer to form the ratchet with two or more teeth any one of which may be engaged with the pawl. The nearer the tooth engaged, by the ratchet, to the heel 11 the greater compression to which the spring 19 will be subjected by movement of the trigger and the more forcible the shot.

10 In Fig. 4 a lever 3^a having a finger piece 4^a is substituted for the lever 3 and the arm 13 is connected by pivot pin 13^a with the dog 14^a having a tooth 15^a for engagement with any one of the teeth of a ratchet 16^a carried at one end of the plunger rod 14. The dog 14^a is formed with a heel 17^a capable of engagement with a shoulder 18^a formed upon the inner wall of the closed end 22 of the barrel. In this construction 15 the trigger 3^a is manually pressed toward the barrel until it engages with a shoulder 19^a of the extension 2. Just previous to this time the heel 17^a will abut the shoulder 18^a and previous to the engagement of the lever 3^a with shoulder 19^a the shoulder 18^a will have moved the dog 14^a upon the pin 13^a and caused said dog to ride out of the teeth of the ratchet 16^a thus permitting the expansion of spring 19 and consequent movement 20 of the plunger rod. The trigger is now moved manually to normal position, shown in full lines, when the toothed end of the dog will gravitate into engagement with the rack 16^a again and the shooter is reset.

25 Just as the trigger 3 engages with the lug 23, or as the heel 17^a engages with the shoulder 18^a, the operator prepares to control by hand the severity of the shot. By manual pressure upon the tube 16 he may nullify a portion of the action of the spring 19 and by practice he may learn to deliver a hard shot or a relatively weak shot as he may desire and consequently a game of pool, billiards or marbles played with the shooter 30 will depend greatly upon the skill and practice of the operator.

What is claimed is:—

1. In a ball shooter comprising a barrel, an extension formed upon said barrel, a ratchet fulcrumed within said extension, means carried by said ratchet for engagement with said extension for limiting the relative movement of said ratchet, a plunger partly disposed within said barrel, a connection between said plunger and ratchet, a trigger fulcrumed upon said extension, connection between said trigger and the said ratchet, and an expansion spring within said barrel for yieldingly retaining said plunger in a predetermined position.

2. In a ball shooter comprising a barrel, an extension formed upon said barrel, a ratchet fulcrumed within said extension, means carried by said ratchet for engagement with said extension for limiting the

relative movement of said ratchet, a plunger adapted for movement through a portion of said barrel, connection between said plunger and said ratchet, a trigger fulcrumed upon said extension for movement toward and away from said extension, connection between said trigger and ratchet whereby movement of the former is transmitted to the latter while said trigger moves toward said extension, and an expansion spring within said barrel and connected to said plunger for yieldingly permitting the same to be drawn into said barrel during the joint movement of said trigger and ratchet, and for forcibly returning said plunger to normal position after the said joint movement is completed.

3. In a ball shooter comprising a barrel, an extension formed upon said barrel, a ratchet fulcrumed within said extension, means carried by said ratchet for engagement with said extension for limiting the relative movement of said ratchet, a plunger carried by said barrel and projected therebeyond, connection between said plunger and ratchet, a trigger fulcrumed upon said extension for movement toward and away from said extension, connection between said trigger and ratchet whereby movement of the former is transmitted to the latter while said trigger moves toward said extension, a trip lug formed upon said extension for engagement with said connection whereby the same is disengaged from said ratchet, a stop ring encircling said plunger within said barrel, a tapered tubular member fast upon said plunger and spaced away from said stop ring and a spring encircling said plunger and abutting said stop ring and tubular member for yieldingly retaining the latter in a predetermined position.

4. In a ball shooter comprising a barrel, an extension formed upon said barrel, a ratchet fulcrumed within said extension, means carried by said ratchet for engagement with said extension whereby movement of said ratchet is limited, a plunger carried by said barrel and projected therebeyond, connection between said plunger and ratchet, a trigger fulcrumed upon said extension, means operatively connecting said trigger and ratchet during movement of said trigger in one direction, a lug carried by said extension for engagement with said last named means at the end of the working movement of said lever, and a spring arranged within said barrel and operatively connected to said plunger for yieldingly retaining the same in a predetermined or normal position.

5. In a ball shooter comprising a barrel, an extension formed upon said barrel, a trigger fulcrumed to said extension, a plunger carried by said barrel, a ratchet carried by said plunger, ratchet engaging means operatively carried by said trigger, said means in-

cluding a heel, a shoulder formed on said barrel for tripping engagement with said heel, and a spring within said barrel and engaging said plunger for yieldingly retaining the same in a predetermined position.

5 In testimony that I claim the foregoing as my own I have hereto affixed my signature

ture in the presence of two subscribing witnesses.

JOHN STRAKA.
